UNITED STATES PATENT OFFICE.

ISIDOR KITSEE, OF PHILADELPHIA, PENNSYLVANIA.

CABLE TELEGRAPHY.

No. 888,096.

Specification of Letters Patent.

Patented May 19, 1908.

Application filed May 1, 1907. Serial No. 371,314.

To all whom it may concern:

Be it known that I, ISIDOR KITSEE, citizen of the United States, residing at Philadelphia, in the county of Philadelphia and State 6 of Pennsylvania, have invented certain new and useful Improvements in Cable Telegraphy, of which the following is a specification.

My invention relates to an improvement 10 in cable telegraphy.

To persons versed in the art of land telegraphy, it is well known that an impulse impressed upon the line of transmission has a greater effect on the home instrument, than 15 on the instrument at the far-off station. In cable telegraphy, and more especially where the true reversal system is used, the effect is just in the opposite direction, that is, the home instrument is not affected by the 20 pulse impressed upon the line in such a degree as the instrument at the other terminal.

In cable telegraphy, the well known siphon recorder is used as the receiver. In this device, the siphon is moved from the zero position either to the right or to the left, in 25 accordance with the polarity of the impulse.

In some of the experiments, impulses were impressed upon the line, in accordance with the system of true reversals, and what seems 30 strange at the first glance is, that the home instrument answered in the desired manner and the characters traced with the aid of the deflecting siphon were of the desired size. The paper at the far off station showed a 35 record of characters of from three to four fold the size.

In some cases where the home instrument was allowed to make somewhat larger characters, (by impressing upon the line impulses 40 of higher electro-motive force), the movement of the far off instrument was so strong that the siphon entirely left the paper. The disadvantage of such behavior is very evident; not only can the characters not well be 45 read, but when the transmission is of a comparatively great speed, the siphon being deflected to such a large extent, cannot return to its zero position before the second impulse arrives, and what is called a "mov- 50 ing of the zero" then takes place. To obviate this difficulty is one of the aims of my invention.

In the drawing, Figure 1 is a diagrammatic view of part of a cable with the receiving 55 device and my invention attached thereto. Fig. 2 represents the continental characters of

the three letters N, O, W, and true fac-simile of the characters as traced by the siphon at the transmitting end, as well as at the far off end in a submarine cable nearly one thousand 60 miles in length.

The cable 1 is grounded at both ends at 2, 2. At the transmitting end a condenser K is inserted in series in the line or cable as well as the opposed batteries B and B', oppo- 65 sitely connected and of different powers. A resistance r may intervene, and the operator's key k is connected as shown. By the manipulation of the key k impulses alternating in polarity are transmitted to the line, 70 as explained in a prior patent granted to me.

3 is the receiving device, here shown as a siphon recorder in conventional sign, but it is obvious that any instrument answering to the impressed impulses may be substituted 75 therefor.

As is illustrated, the coil proper of the siphon recorder is not connected directly in the line, but is in shunt to the variable condenser 4. In series with the shunt wires 5 80 are the variable resistances 6, 6, and the variable condenser 7.

In Fig. 2, a designates the three letters N, O, W, and their respective continental characters; b designates the record as made 85 by the home instrument, and c designates the record as made by the far off instrument.

Careful experiments established the fact, that the line of transmission, having such large capacity, augments—so to speak—the 90 force of the impressed impulse, and as the capacity and resistance of the line varies in accordance with the temperature of the water and other changes in the line, it is necessary to remove the receiving device from the direct path of such impulses. For this reason and for the further reason that the surging of such waves, as are due to earth currents and the like, I have placed in the line a condenser and, as the capacity of the condenser has to 95 vary in accordance with the conditions of the line, I had recourse to, what is known as, a "variable condenser," that is, a device, the capacity of which may be varied according to the will of the operator. In shunt with 100 this variable condenser, I place the receiving device. The impulse, therefore, when impressed upon the line, may in such case be augmented or not, but only such part of the impulse as the operator requires will flow 105 through the shunt, for the reason that the condenser may be made to offer a very small

or very large capacity, and the broadening out of this impulse due to the capacity of the condenser can—as is apparent—also be regulated according to the will of the operator. 5 Its influence, therefore, on the siphon recorder or other receiving device is easily controlled through the manipulation of the condenser.

To so arrange matters, that only a decided 10 change in the polarity of the condenser should affect the receiving device, I have placed the resistances and a second condenser in the shunt, in which the receiving device is placed. Through this arrangement 15 the surging of the electric waves—foreign to the impressed impulses—will not affect to any serious degree the movable part of the receiving device.

Having now described my invention, what 20 I claim as new and desire to secure by Letters Patent is:—

1. In a telegraph system, the combination with a cable having great distributed capacity, of a condenser included therein, and a 25 shunt circuit including an adjustable portion of the capacity of said condenser and a receiving instrument.

2. In a telegraph system, the combination with a cable having great distributed capacity, of a condenser connected in said cable, 30 and a circuit in shunt to said condenser including a receiving instrument.

3. In a cable telegraph system, the combination with a cable having great distributed capacity, of a condenser included therein, and a shunt circuit including an adjustable portion of said condenser and a polarized 35 receiving instrument.

4. In a cable telegraph system, the combination with a cable having great distributed capacity, of a condenser included therein, and a shunt circuit including a receiving 40 instrument and a condenser serially connected.

45 5. In a cable telegraph system, the combination with a cable having great distributed capacity, of a condenser included therein, and a shunt circuit including a condenser

and a polarized receiving instrument serially connected.

6. In a cable telegraph system, the combination with a cable having great distributed capacity, of a condenser included therein, and a shunt circuit including a resistance, a condenser, and a receiving instrument. 50

7. In a cable telegraph system, the combination with the line, of a condenser included therein, and a shunt circuit including a polarized receiving instrument, a resistance, and a condenser serially connected. 55

8. In a cable telegraph system, the combination with a cable having great distributed capacity, of means for impressing upon said cable impulses alternating in polarity, a condenser in said cable at the receiving end, and a polarized receiving instrument connected in a circuit in shunt to said condenser. 60

9. In a cable telegraph system, the combination with a cable having great distributed capacity, of means for impressing upon 70 said cable impulses alternating in polarity, an adjustable condenser in said cable at the receiving end, and a circuit in shunt to said condenser including a condenser and a polarized receiving instrument.

10. In a cable telegraph system, the combination with a cable having great distributed capacity, of means for impressing thereon impulses alternating in polarity, a condenser in said cable at the receiving end, a 80 circuit in shunt to said condenser, and the winding of a siphon recorder included in said shunt circuit.

11. The method of transmitting signals over a cable having great capacity, which 85 consists in impressing upon the cable impulses alternating in polarity, and subjecting the received impulses to electro-static reactance and reproducing the signals by the resultant impulses.

In testimony whereof I affix my signature in presence of two witnesses.

ISIDOR KITSEE.
